(57) **CLAIM**

The ornamental design for gas can rack, as shown and described.

DESCRIPTION

FIG. 1 is an isometric view of the gas can rack of the invention (broken lines of the Humvee/Hummer are for illustrative purposes only and form no part of the claimed design);

FIG. 2 is a front view in elevation of the gas can rack of FIG. 1;

FIG. 3 is a right side view in elevation of the gas can rack of FIG. 1 (left side identical);

FIG. 4 is a rear view in elevation of the gas can rack of FIG. 1;

FIG. 5 is a top plan view of the gas can rack of FIG. 1; and, FIG. 6 is a bottom plan view of the gas can rack of FIG. 1. The gas can rack is shown on an enlarged scale in FIGS. 2-6.

1 Claim, 3 Drawing Sheets
